UNITED STATES PATENT OFFICE.

PETER M. YOUNG, OF CHICAGO, ILLINOIS.

SWIVEL AND RING.

1,271,647.

Specification of Letters Patent.

Patented July 9, 1918.

Application filed March 13, 1917, Serial No. 154,589. Renewed May 20, 1918. Serial No. 235,726.

To all whom it may concern:

Be it known that I, PETER M. YOUNG, a citizen of the United States, residing at Chicago, in the county of Cook and State 5 of Illinois, have invented new and useful Improvements in Swivels and Rings, of which the following is a full, clear, concise, and exact description, reference being had to the accompanying drawings, forming a 10 part of this specification.

My invention relates to improvements in swivels and rings used by jewelers and others and has for its object the production of a device in which the ring or swivel holding 15 a watch or any other object may be automatically locked and held against opening.

A further object is the production of a device in which a complete closure is formed without liability to its dropping open.

20 A further object is the production of a device of simple construction, one that can be cheaply manufactured and one not liable to disarrangement of parts.

These and such other objects as may here- 25 inafter appear are attained by my device, embodiments of which are illustrated in the accompanying drawings, in which—

Figure 1 represents the side elevation of my improved swivel in open position, partly 30 broken away; and

Fig. 2 represents a side elevation of a ring with parts broken away.

Like numerals of reference indicate like parts in the several figures of the drawings.

35 Referring now to the drawings, 1 represents the swivel base, 2 the curved ring portion terminating in a reduced end 3 provided with an opening 4.

The chain support 5 carrying at its lower 40 end a ring 6 is pivotally mounted on the swivel support at 7, the swivel closure 8 extending upwardly therefrom, and having a reduced portion 9 corresponding to the similar portion 3 on the ring, and carrying a pin 10 placed at the proper angle and being 45 of a proper size to enter within the opening 4 when the swivel is closed.

In Fig. 2 the ring 11 is broken as shown at 50 12 and reduced at one end as shown at 13 and provided with an opening 14 within said reduced portion. A curved closure segment 15 is pivotally mounted at 16 on the opposite end of the ring, and provided with a reduced end 17 and a pin 18, the reduced 55 portion and pin being adapted to register with the reduced portion and opening on

the opposite end of the ring. A supporting link 19 is rigidly secured to the closure 15 near its pivotal point 16 and extending outwardly therefrom, adapted to engage the 60 lower link of a chain 20. It will be noted that an upward pull on the chain 20 swings the closure 15 up against the reduced end 13 causing the pin 18 to enter within the opening 14 locking the link together. The 65 configuration of the opening and pin is such that the pin when entering the opening springs the end slightly out locking the parts together against ordinary movement, or if desired, the joint at 16 may be made 70 rather tight to prevent the closure from coming open.

In any event, however, as the link is supposed to have a watch or ornament 21 suspended at its lower end and to be supported 75 at its upper end by the chain, it is practically always under tension, so there is little danger of its coming open unless it is forced open in order to remove the watch or ornament from the link. In order to open it 80 it is simply necessary to press down on the lower link of the chain or on the supporting link 19, thus forcing the closure 15 back into the position shown in the figure, when the watch or ornament can be slipped off. 85

In the operation of the swivel shown in Fig. 1 the chain 22 is secured to the ring 6 and a downward pull on the chain swings the swivel arm 5 down to the point 7 until its back face 23 strikes the inner face 24 of 90 the slot within the swivel base in which it travels. At the same time the swivel closure is forced forward causing the reduced portions 9 and 3 to come together forming a 95 continuous surface and causing the pin 10 to enter the opening 4. The pin and the opening may be so arranged as to require a slight pressure to cause the pin to enter the opening springing the end of the swivel outwardly and in a sense locking the members together, or in this construction the joint between the swivel base and the swivel may be tight so as to do away with the necessity for any spring member at the closure.

Inasmuch as the pull against the swivel is generally in a direct line with the swivel itself there is very little, if any, danger of the closure coming open unless lateral pressure is applied to the arm 5 forcing it open. 105

The introduction, however, of slight spring means in both the ring and the swivel can 110

be easily effected and make a somewhat more efficient structure.

While I have illustrated my device as adapted to rings and swivels, other adaptations may be made without departing from the spirit of my invention.

Having thus described my invention, what I claim as new and desire to secure by Letters Patent is:

10. An article of the class described comprising a supporting base provided with a slot, an open ring having a reduced end provided

with an opening mounted on said base, a segmental closure pivotally mounted on said base opposite the reduced end, a pin mounted thereon, a flattened arm integral with said closure and extending downward therefrom and so positioned that a pull on said arm forces it within the slot and forces the pin on the opposite end within the opening in the ring forming a continuous ring. 15 20

In witness whereof I have hereunto subscribed my name.

PETER M. YOUNG.
